(74) Attorney, Agent, or Firm—Douglas H. Tulley, Jr.

(57) **CLAIM**

I claim the ornamental design for the napkin dispenser cartridge, as shown and described.

DESCRIPTION

FIG. 1 is a partially elevated, angled view of the napkin dispenser cartridge.

FIG. 2 is a front view of the napkin dispenser cartridge shown in FIG. 1.

FIG. 3 is a side view of the napkin dispenser cartridge shown in FIG. 1.

FIG. 4 is a back view of the napkin dispenser cartridge shown in FIG. 1.

FIG. 5 is a top view of the napkin dispenser cartridge shown in FIG. 1; and,

FIG. 6 is a bottom view of the napkin dispenser cartridge shown in FIG. 1.
